UNITED STATES PATENT OFFICE.

EDWIN O. BRANINGTON, OF ROCHESTER, NEW YORK, ASSIGNOR OF ONE-HALF TO
OSCAR A. PETERS, OF ROCHESTER, NEW YORK.

WATER MOTOR.

Application filed January 9, 1925. Serial No. 1,496.

The present invention relates to water wheels of the impact or "Pelton" type, and an object thereof is to largely overcome, by uniquely constructed floats or buckets, the usual losses in energy and thus provide a wheel of this character operating in such manner as to convert an increased amount of energy of the impinging stream into useful work. By way of illustration, it may be 10 stated that tests of a ten inch wheel, with a $\frac{1}{8}$ inch nozzle, under 50 lbs. pressure, gave 3585 R. P. M. and 92% efficiency.

Another object of the invention is to utilize the full force of the impinging stream 15 or jet just as it leaves the discharge nozzle and, also, to have the floats enter and leave the path of the propelling jet with the least possible obstruction to the jet.

Another object of the invention is to have 20 the full force of the jet acting against a plurality of floats at the same time.

A further object of the invention is to provide a plurality of floats mounted for oscillatory movement, each of which is in the 25 form of two arm lever or bell-crank, one arm comprising a bucket member and the other extending normally in the direction of rotation of the wheel, each member in turn directly receiving the impact of the jet and 30 in such manner as to cause the least possible angular deflection of the stream.

A further object of the invention is to provide a wheel of the character described in 35 which floats mounted for oscillatory movement project laterally and are arranged on a side face of the wheel and have their axes radial to the axis of the wheel.

And, a still further object of the invention 40 is to provide a water motor of durable, simple and inexpensive construction.

To these and other ends the invention consists of certain parts and combinations of parts as will be fully set forth in the following description and particularly defined in 45 the appended claims.

The accompanying drawings illustrating the invention are as follows:

Figure 1 is a top plan view of the motor and support therefor.

Fig. 2 is a side view of the motor with the casing and supporting frame shown in section on the line 2—2, Fig. 1.

Fig. 3 is an enlarged fragmentary view of

parts as seen in Fig. 2 and showing the manner in which the floats receive the impact of 55 the propelling jet.

Fig. 4 is a sectional detail on the line 4—4, Fig. 2, showing one of the floats in face view.

Fig. 5 is an enlarged end view of one of the floats with the bucket member shown in 60 section as on the line 5—5, Fig. 4.

Fig. 6 is a view similar to Fig. 2 showing a modification of the invention.

Fig. 7 is an enlarged sectional detail on the line 7—7, Fig. 6.

And, Figs. 8 and 9 are diagrammatic illustrations showing the manner in which the floats of the wheel seen in Fig. 6 are impinged by the propelling jet.

Similar reference numerals refer to similar parts throughout the several views.

Referring first to Figs. 1 to 5, inclusive:

The numeral 1 indicates a wheel which is fixed to a shaft 2 mounted in ball bearings 3 carried, in this instance, by arms 4 upstanding from a plate or bed 5 secured to frame pieces 6. The side faces of this wheel project beyond the peripheral face 8 so as to form an annular channel 9 across which extend a plurality of regularly spaced axially arranged pins 10 which have bearing in the side walls of the channel.

Mounted on these pins 10 for oscillatory movement are floats each of which is in the form of a two arm lever with the arms extending substantially at right angles to each other, one arm being longer than the other and comprising a bucket member 11 while the shorter arm 12, when the float is swung outwardly extends forwardly, or in the direction of rotation of the wheel, from the inner end of the bucket member and lies against the bottom 8 of the channel, the pivotal connection being substantially at the juncture of the two arms. In other words, 85 each float comprises a bucket member pivoted at its inner end to oscillate about an axis parallel to the axis of the wheel and having at its inner end a forwardly projecting arm adapted to abut the face of the wheel and 90 form a stop for limiting movement of the bucket member beyond a plane radially of the wheel. Fig. 2 shows the positions of the several floats when the wheel is at rest.

The impinging stream is directed through 95 a nozzle 13 which, in this instance, is inclined

at such an angle that the jet will be projected substantially tangential to the wheel and into a short sluice 14 through which the floats travel, this sluice opening into an enlarged chamber 15 having connection, not shown, with a suitable outlet for the water. The wheel is inclosed within a suitable casing 16 secured by bolts 17 to the bed plate 5, and this casing is formed with an aperture 10 for receiving the nozzle 13, the latter being supported in a sleeve 18 arranged in the casing at the intake end of the sluice 14.

The bucket members 11 of the floats it will be noticed have their ends and under 15 surfaces rounded so as not to cause any sharp angular deflection of the jet, and owing to the flexible mounting of the floats the discharge opening in the nozzle 13 may be located extremely close to the outer periphery of the motor which insures the floats 20 receiving full impulse of the stream at the nozzle.

The wheel, in this instance, rotates anti-clockwise and as each succeeding bucket 25 member 11 strikes the jet directly at the discharge from the nozzle 13, see Fig. 3, it is caused to swing in the direction of the arrow —x—, thus moving its arm 12 into the path of the stream, the arm receiving 30 direct impact from the jet while the bucket member rides on the jet, as indicated by the bucket shown in dotted lines at 19, Fig. 3. At this time the next preceding float has 35 reached the dotted line position indicated at 20. Impact of the jet against a short arm 12 causes its bucket member 11 to swing in the reverse direction to the arrow —x— to enter the path of the jet and receive its direct impact.

From the foregoing it will be seen that 40 due to the flexible mounting of the floats there will be less deflection of the impinging stream than if they were rigidly secured to the wheel, and, also, that the stream will be 45 acting with full force against the short arm of one float and the bucket member of the next preceding one so that the greatest possible energy of the stream is utilized with the least possible deflection thereof. Furthermore, the water is discharged from the 50 bucket members before they begin to rise and the flexible mounting thereof also is a means of minimizing the resistance offered by the air as the floats travel upward.

In order to avoid loss of energy owing to 55 dead water pocketing in the bucket members and to spread the water more evenly over the surface of the bucket, each such member is divided longitudinally by a partitioning wedge 21.

In Figs. 6 to 9, inclusive, there is shown 60 a modification of the invention in which the wheel 22 within a casing 23 and secured to a shaft 24 rotatably mounted in bearings 25 is formed with an annular channel 26 in one

of its side faces, the pins 27 which form bearings for the floats, extending radially and having bearing in the walls of the channel. In this modification the floats are shown as formed of sheet metal and comprise 70 bucket members 28 and short arm members 29 at substantially right angles to each other, the arms projecting from the bucket members in the direction of travel of the wheel and co-operating with the bottom of the 75 channel to limit outward movement of the bucket members. In this modification, as in the one hereinbefore described, the jet, which is projected from a nozzle 30 extending laterally from a supply pipe 31, impinges against both the arm members and the buckets of the several floats so that an oscillatory movement of the floats is effected. With this form of motor no sluice 80 is employed and the outlet for the water 85 is through an opening 32 in the bottom of the casing which communicates with a discharge chamber 33.

It will of course be understood that various changes and modifications may be 90 made in the details of construction of both modifications of the invention without departing from the spirit thereof.

What I claim is:

1. A pivotally supported float for a water 95 motor and comprising two arms at substantially right angles to each other, one of said arms being formed as a bucket and having a rounded outer end and under surface.
2. A pivotally supported float for a water 100 motor and comprising two arms at substantially right angles to each other, one of said arms being formed as a bucket and having a rounded outer end and under surface and a longitudinally extending web in the center 105 of its dished portion.
3. In a water motor, the combination of a wheel, a plurality of floats mounted for oscillatory movement on the wheel, each comprising two arms of unequal length at substantially right angles to each other, and a nozzle, both arms of each succeeding float receiving direct impact from the jet from 110 said nozzle as the wheel rotates, the forward part of the under surface of the long arm 115 of each float being inclined to permit the end edge of the arm to pass close to the discharge end of the nozzle.
4. In a water motor, the combination of a wheel, a plurality of floats mounted for oscillatory movement on the wheel, each comprising two arms of unequal length at substantially right angles to each other, a nozzle and a sluice, both arms of each succeeding float receiving direct impact from the jet from 120 said nozzle, said jet impinging against one arm of one float and against the other arm of the next preceding float while such two floats are passing through said sluice, the forward part of the under surface of the 125
5. In a water motor, the combination of a wheel, a plurality of floats mounted for oscillatory movement on the wheel, each comprising two arms of unequal length at substantially right angles to each other, a nozzle and a sluice, both arms of each succeeding float receiving direct impact from the jet from 130 said nozzle, said jet impinging against one arm of one float and against the other arm of the next preceding float while such two floats are passing through said sluice, the forward part of the under surface of the

long arm of each float being inclined to permit the end edge of the arm to pass close to the discharge end of the nozzle.

5. In a water motor, the combination of a wheel, a plurality of floats mounted for oscillatory movement on the wheel, each comprising a bucket member and an arm projecting from the inner end of the bucket member in the direction of rotation of the 10 wheel, a nozzle, and a sluice, both members of each float receiving direct impact from the jet from said nozzle, said jet impinging against the arm member of one float and against the bucket member of the next preceding float while such two floats are passing through said sluice, the forward end of the 15 bucket member of each float being cut back to permit the top end edge to pass close to the discharge end of the nozzle.

20 6. In a water motor, the combination of a wheel, a plurality of floats mounted for oscillatory movement on the wheel, each float comprising two arms of unequal length arranged at substantially right angles to each other and the longer arm having an inclined under surface at its forward end, a nozzle, 25 and a sluice, the inclined surface of the longer one of said arms striking the jet close to the mouth of said nozzle whereupon the float is caused to swing to carry the longer arm first away from and then into said jet, both 30 arms receiving direct impact from the jet during such oscillatory movement and the shorter arm co-operating with a face of the wheel to limit outward swing of the longer arm.

wheel, a plurality of floats mounted for oscillatory movement on the wheel, each float comprising two arms of unequal length arranged at substantially right angles to each other and the longer arm having an inclined under surface at its forward end, a nozzle 35 and a sluice, the inclined surface of the longer one of said arms striking the jet close to the mouth of said nozzle whereupon the float is caused to swing to carry the longer arm first away from and then into said jet, both 40 arms receiving direct impact from the jet during such oscillatory movement and the shorter arm co-operating with a face of the wheel to limit outward swing of the longer arm.

45 8. In a water motor, the combination of a wheel, a plurality of floats mounted for oscillatory movement on the wheel, each float comprising a bucket member and an arm member projecting from the inner end of the arm member in the direction of rotation of the wheel, a nozzle, and a sluice, the bucket member of each float having its under surface cut back at its forward end and striking the jet close to the mouth of said nozzle 50 whereupon the float is caused to swing to carry the bucket member first away from and then into said jet, both said arm and said bucket member receiving direct impact from the jet during such oscillatory movement and while the float is passing through said sluice.
